CLAIM

The ornamental design for drinkware, as shown and described.

DESCRIPTION

FIG. 1 is a perspective view of drinkware showing my new design;

FIG. 2 is a first elevation view thereof;

FIG. 3 is a second elevation view thereof;

FIG. 4 is a third elevation view thereof;

FIG. 5 is a fourth elevation view thereof;

FIG. 6 is a top view thereof; and,

FIG. 7 is a bottom view thereof.

The broken lines shown in the figures are for illustrative purposes only, and form no part of the claimed design.
